HYDROCARBON CONVERSION

Roland B. Day and Elmer R. Kanhofer, Chicago,
Ill., assignors to Universal Oil Products Com-
pany, Chicago, Ill., a corporation of Delaware

Application January 21, 1941, Serial No. 375,106

7 Claims. (CL. 196—52)

This invention relates to improvements in the method of effecting conversion of hydrocarbon oil in a combination catalytic and pyrolytic cracking system in which relatively high yields of high octane rating gasoline are produced. More specifically the invention relates to improvements in the method of conducting the catalytic conversion reaction and provides a more accurate means for controlling temperatures and space velocities in the catalytic conversion treatment.

In the catalytic cracking of hydrocarbons to produce lower boiling products therefrom, it has been found that insufficiently converted hydrocarbons formed in the process contain relatively large quantities of coke forming hydrocarbons which are reduced to coke if returned to the catalytic cracking step with no intermediate treatment for their removal or conversion into hydrocarbons more susceptible to catalytic cracking.

It is not considered advisable to treat such insufficiently converted hydrocarbons from catalytic cracking to remove the carbon forming constituents contained therein by solvent extraction, for example, but more generally by pyrolytic cracking. In the operations involving the pyrolytic treatment of the insufficiently converted hydrocarbons from a catalytic cracking process wherein at least a portion of the reaction products formed in the pyrolytic cracking step is supplied to the catalytic cracking step, it has been shown that the deposit of carbonaceous substances on the catalyst is less in such cases for the same quantity of oil converted than in a once-through operation on a virgin stock. In the latter type of operation, however, relatively large quantities of gasoline are formed in the pyrolytic cracking step and this gasoline will ordinarily be from 10 to 15 points lower in octane rating than that formed in the catalytic cracking step with the result that the octane rating of the final blend of the two distillates formed in the two cracking steps is considerably below that which may be obtained when recycling all of the insufficiently converted hydrocarbons direct to the catalytic cracking step neglecting in such cases the undesirable feature of high carbon deposition normally associated with such a process.

It has been found that the octane rating of the gasoline produced in the pyrolytic cracking step may be improved by commingling such gasoline with the stream of hydrocarbon oil to be converted in the catalytic cracking step. The

improvement of the octane rating of this material is probably due to an isomerizing effect, and although the conditions employed in the catalytic cracking step are not optimum for the isomerizing reaction, improved results are definitely shown. The relatively low liquid hourly space velocities employed in the catalytic cracking step as compared to the higher space velocities desirable in the isomerizing reaction will cause an increased gas production when gasoline boiling range hydrocarbons are returned to this step as compared to the gas production when the pyrolytically formed gasoline is separately treated.

In our invention, to obviate some of the undesirable features associated with the processes previously mentioned, we provide a catalyst zone separate from the initial catalyst cracking zone to which all of the conversion products from the catalytic cracking step plus the pyrolytically formed gasoline is supplied whereby conditions in such separate zone may be controlled within the limits optimum for improving the octane rating of the pyrolytically formed gasoline in the absence of any substantial amount of cracking to lighter products and coke. Preferably also and in accordance with the objects of the invention, the pyrolytically formed gasoline with or without the separation of light normally gaseous hydrocarbons is separately heated and the heated distillate thereafter commingled with the conversion products from the catalytic cracking step, the heating of such distillate being controlled so that the temperature of the final mixture is optimum for the reaction to be accomplished. The volume of such separate catalyst zones may be controlled within desirable limits so that the space velocities of the hydrocarbon reactants brought in contact with the catalyst contained therein are optimum for the process.

In one embodiment the invention comprises subjecting a readily vaporizable hydrocarbon oil to contact with a mass of cracking catalyst to effect conversion into lower boiling products, commingling the conversion products with fractionated vapors separated as hereinafter set forth and passing the mixture in contact with a separate mass of cracking catalyst, fractionating the resultant conversion products to separate fractionated vapors boiling substantially in the range of gasoline from the insufficiently converted hydrocarbons, cooling and condensing said fractionated vapors, subjecting said insufficiently converted hydrocarbons to pyrolytic cracking,

fractionating vaporous reaction products formed in the pyrolytic cracking step to separate fractionated vapors boiling substantially in the range of gasoline, light reflux condensate, and a heavier reflux condensate, subjecting the last mentioned fractionated vapors to treatment in the manner hereinbefore set forth, supplying said light reflux condensate to the catalytic cracking step, and supplying said heavier reflux condensate to the pyrolytic cracking step.

In still another embodiment the invention may comprise passing a readily vaporizable hydrocarbon oil heated to a cracking temperature in contact with a mass of cracking catalyst to effect conversion into lower boiling products, commingling the conversion products with fractionated vapors separated as hereinbefore set forth and passing the resultant mixture in contact with a separate mass of cracking catalyst at a relatively higher space velocity than that employed in the first mentioned mass, fractionating the resulting conversion products to separate fractionated vapors boiling substantially in the range of gasoline from insufficiently converted hydrocarbons, cooling and condensing said fractionated vapors, subjecting said insufficiently converted hydrocarbons to pyrolytic conversion together with a difficultly vaporizable hydrocarbon oil, fractionating vaporous reaction products formed in the pyrolytic cracking step to separate fractionated vapors boiling substantially in the range of gasoline, a light reflux condensate, and a heavier reflux condensate, subjecting the last mentioned fractionated vapors to treatment in the manner hereinbefore set forth, supplying said light reflux condensate to the catalytic cracking step and supplying said heavier reflux condensate to the pyrolytic cracking step.

Fig. 1 of the accompanying diagrammatic drawing illustrates in conventional side elevation one specific form of the apparatus to which the improvements set forth in this invention may be applied. Fig. 2 illustrates a modified form of reactor from that shown in Fig. 1. It is understood, of course, that the invention herein disclosed is not to be limited to the particular type of apparatus illustrated and described but may be applied, for example, in operations in which a flowing bed of powdered catalyst is employed in the catalytic cracking section or in a system employing slurry catalyst cracking, or to various other combinations of catalytic and pyrolytic cracking and is directed to a process in which a pyrolytically formed gasoline is produced concurrently with the production of catalytically formed gasoline.

In the process illustrated in the accompanying drawing charging stock may comprise, for example, a relatively light readily vaporizable hydrocarbon oil in which case such oil is introduced or supplied to the catalytic cracking step or in some cases the charging oil may comprise a relatively heavy difficultly vaporizable hydrocarbon oil and in such cases it is supplied to the pyrolytic cracking step. In still other cases the charge may comprise a composite of relatively light and relatively heavy oils and in such cases it is usually desirable to supply this oil to the pyrolytic cracking step either directly to the heating coil but more generally to the fractionator receiving the vaporous reaction products from the pyrolytic cracking step.

Referring now to the drawing, a relatively light readily vaporizable hydrocarbon oil, which in some cases may comprise the sole charging stock

for the process, is introduced through line 1 containing valve 2 to pump 3. Pump 3 discharges through line 4 containing valve 5 into heating coil 6. Preferably also, the relatively light oil in line 4 is commingled with light reflux condensate separated in the manner to be described and, as previously inferred, such light reflux condensate may in some cases comprise the sole charge to this step. The oil in passing through heating coil 6 is vaporized and heated to a cracking temperature by means of heat supplied from furnace 7. The cracking temperature to which such oil is heated will in most cases fall within the range of 800 to 1200° F. and usually within the range of 900 to 1050° F. Heated vapors leaving coil 6 under a pressure of from substantially atmospheric to 200 pounds per square inch or thereabouts pass through line 8 and may be introduced to either reactor B by way of valve 9 or to reactor A by way of line 10 containing valve 11.

The system illustrated in the accompanying drawing is shown as consisting of two reactors A and B in which catalytic cracking is accomplished and two communicating reactors A' and B' in which catalytic treatment of the pyrolytically formed gasoline and the catalytic conversion products is accomplished. In the catalytic cracking of hydrocarbons, it is general practice to employ at least two reactors or pairs of reactors, as in the case here illustrated, in order that the cracking reaction may be carried out continuously, the only interruptions being when switching the stream of hydrocarbon reactants from one reactor to the other. The purpose of employing at least two reactors is, of course, readily understood since the cracking reaction is ordinarily accompanied with the deposition of carbonaceous substances which must be removed by period frequent regeneration and thereby maintain the bed or beds of catalyst in a highly active state. In the process of the invention herein described, it is intended that regeneration be accomplished by well known methods of which no description is necessary.

The reactors employed in a process of this kind may comprise any of the well known types, especially those heat exchanger type containing a plurality of tubular elements in which the catalyst is placed and wherein provisions are made for passing a suitable heat convective fluid in contact with said tubular elements to supply heat during conversion and remove heat during regeneration, and those of the adiabatic type which contain one or a plurality of beds of catalytic material through which the hydrocarbon reactants pass either in series or parallel.

Catalysts which have been found to be effective in the catalytic cracking of hydrocarbon vapors and in the treatment of pyrolytically formed gasoline may comprise, for example, powder, pellets or granules of synthetically prepared purified silica or other siliceous and refractory materials composed with one or more of the compounds selected from the group consisting of alumina, zirconia, and thoria. In addition, the hydrosilicates of alumina, acid treated clays, or the like, have also been found to be effective in the cracking treatment of hydrocarbon vapors. Although the catalysts above recited are generally considered to be the preferred catalysts their use is not to be construed as a limiting feature, for various other catalysts well known to those in the art may be employed within the broad scope of the invention.

The catalyst enumerated above will, in general, promote the desired catalytic cracking of hydrocarbon reactants heavier than gasoline, however, in the catalytic treatment following the conversion step to which the pyrolytically formed gasoline is supplied, better results may be obtained when using the synthetically prepared catalyst, such as those of the silica-alumina or silica-alumina-zirconia type, but it is not intended that catalysts of the acid treated clay type be excluded from use in such process, for these catalysts will also exert some beneficial effect.

Conversion products leaving either reactor A or B are directed through respective lines 12 and 13 containing respective valves 14 and 15 and are commingled with a heated pyrolytically formed distillate supplied in the manner to be described following which the resulting mixture is introduced to either one of the reactors A' or B' depending, as in the above case, upon whether at such instance the reactor is employed in processing or the catalyst contained therein is undergoing regeneration. The invention contemplates switching streams of hydrocarbons introduced to reactors A' and B' at the same instant that the stream of reactants is switched between reactors A and B. While catalytic conversion is being accomplished in reactor A the catalytic treatment is accomplished in reactor A' and at the same time the catalyst contained in reactors B and B' is undergoing regeneration. It follows therefore that when reactors B and B' are used in processing the catalyst in reactors A and A' is undergoing regeneration. Preferably also and in accordance with the objects of the invention, the liquid hourly space velocity (liquid volume of hydrocarbons per unit volume of catalyst) employed in reactors A' and B' is relatively high as compared with those employed in reactors A and B, for whereas space velocities of the order of .5 to 10 are employed in reactors A and B, space velocities of the order of 10 to 20 are employed in reactors A' and B'. Reaction temperatures within reactors A' and B' are preferably of the order of 800 to 1200° F., but it is more general practice to employ temperatures below 1000° F. The invention also contemplates substituting a single reactor for the double reactor, such as A and A'. Fig. 2 illustrates this modified form of reactor. In this figure appurtenances which are the same as those shown in Fig. 1 have received the same legends. Thus, when processing reactor AA', heated vapors in line 8 are directed through line 10 and valve 11 into one end of the reactor and pass in contact with a body of catalyst maintained therein. Conversion products are withdrawn from the opposite end of reactor AA' through line 16 and valve 17 for further treatment, as will be described in connection with Fig. 1. Heated pyrolytically cracked distillate is introduced into reactor AA' at an intermediate point and passes with the heated vapors through the remaining portion of the reactor. Thus the pyrolytically formed distillate to be treated in the manner above described may be introduced to the single reactor at some intermediate point so that the time in which these hydrocarbons remain in contact with the catalyst is not in excess of the time required to effect the desired improvement in octane rating.

With reactors A and A' on process conversion products leaving reactor A' are directed through line 16 containing valve 17, and with reactors B and B' on process conversion products leaving

reactor B' are directed through line 18 containing valve 19 into line 16. In any event, conversion products in line 16 are supplied to fractionator 20. Fractionator 20 together with the condensing and collecting equipment in communication therewith is preferably operated at a pressure of substantially the same order as that employed on the outlet of reactors A' and B'. Conversion products supplied to fractionator 20 are fractionated therein to separate fractionated vapors preferably comprising a full boiling range gasoline, such as, for example, one having a 400° F. end point from insufficiently converted hydrocarbons and the latter condensed within the fractionator and removed as a liquid from the lower portion thereof in the manner to be described.

Fractionated vapors separated in fractionator 20 are conducted through line 21 containing valve 22 to cooling and condensation in condenser 23. Distillate together with undissolved and uncondensed gases leaving condenser 23 is directed through line 24 containing valve 25 into receiver 26 wherein the distillate and gases are collected and separated. Undissolved and uncondensed gases collected and separated in receiver 26 are removed therefrom by way of line 27 containing valve 28 and recovered as a product of the process. A portion of the distillate separated in receiver 26 may be returned to the upper portion of fractionator 20 by well known means, not shown, as a refluxing and cooling medium in controlling the end point of the fractionated vapors and the residual portion thereof removed from receiver 26 by way of line 29 containing valve 30 and recovered as a product of the process or subjected to any desired further treatment.

Insufficiently converted hydrocarbons separated in fractionator 20 are directed through line 31 containing valve 32 to pump 33 which discharges through line 34 containing valve 35 into heating coil 36. In some operations, also, heavy reflux condensate and/or a relatively heavy oil containing difficultly vaporizable hydrocarbons may be commingled with the insufficiently converted hydrocarbons in line 34 in the manner to be described and the total mixture introduced to heating coil 36. The oil supplied to coil 36 in passing therethrough is heated to a cracking temperature of the order of 850 to 1000° F., or thereabouts, by means of heat supplied from furnace 37. The heated oil leaving coil 36 is directed through line 38 containing valve 39 and introduced into reaction chamber 40 which is preferably operated under a superatmospheric pressure of the order of 100 to 500 pounds per square inch and wherein cracking instigated in the heating coil is allowed to proceed to a greater degree of completion.

Reaction products leaving chamber 40 are directed through line 41 containing valve 42 into vaporizing and separating chamber 43 which is preferably operated at a reduced pressure relative to that employed in chamber 40 and the pressure maintained therein will usually fall within the range of 50 to 200 pounds per square inch. Vaporous reaction products are separated from non-vaporous reaction products in chamber 43 and the latter substantially further vaporized to form a non-vaporous liquid residue which is recovered as a product of the process by way of line 44 containing valve 45. Vaporous reaction products together with vapors evolved within chamber 43 are directed through line 46 containing valve 47 into fractionator 48 and this

fractionator may be operated at a pressure of substantially the same order as that employed on the outlet of chamber 43. The vaporous reaction products are fractionated within fractionator 48 to separate the fractionated vapors from higher boiling hydrocarbons, containing in some instances only low boiling products, such as, for example, hydrocarbons having 5 carbon atoms and less to the molecule. Generally, however, this fraction will include hydrocarbons boiling within the range of gasoline. The higher boiling hydrocarbons separated in fractionator 48 are condensed therein as reflux condensate and may at times be collected as a total reflux condensate while at other times further separation may be accomplished in fractionator 48 to separate a light reflux condensate from the heavier reflux condensate.

Fractionated vapors separated in fractionator 48 are conducted through line 49 and may be directed through valve 50 to cooling and condensation in condenser 51. Distillate together with undissolved and uncondensed gases from condenser 51 is directed through line 54 containing valve 55 to collection and separation in receiver 56. Undissolved and uncondensed gases collected and separated in receiver 56 are removed therefrom by way of line 57 containing valve 58 and recovered as a product of the process. In an operation involving the removal of only low end point fractionated vapors from fractionator 48, such as hydrocarbons having 5 carbon atoms and less to the molecule, the distillate collected in receiver 56 in such instance is removed therefrom by way of line 59 containing valve 60 and recovered as a product of the process. In an operation involving the removal of fractionated vapors from fractionator 48 over the full boiling range of gasoline, the distillate in excess of that required in refluxing and cooling the upper portion of fractionator 48 is directed through line 61 containing valve 62 to pump 63. Pump 63 discharges through line 64 containing valve 65 into heating coil 66. In this latter type operation provisions are also made for bypassing the cooling and condensing step, in which case the fractionated vapors in line 49 are conducted through line 52 containing valve 53 into line 64 by means of which they are supplied to coil 66.

Fractionated vapors supplied to coil 66, either as a liquid or vapor, are heated therein to a temperature of the order of 800 to 1100° F. by means of heat supplied from furnace 67. Heated vapors leaving coil 66 are directed through line 68 containing valve 69 into line 70 following which such heated vapors are directed either through valve 71 into line 12 or valve 72 into line 13 for treatment in the manner previously described.

The total reflux condensate separated in fractionator 48 is conducted through line 73 containing valve 74 to pump 75. Pump 75 discharges through lines 76 and 77 and valve 78 into line 83 by means of which such reflux condensate is supplied to line 4, commingling with the relatively light oil for treatment in the manner previously described.

In an operation involving both the separation of light and heavy reflux condensate the two condensate fractions are separately removed from fractionator 48 and subjected to treatment in the manner to be described. Heavy reflux condensate in such cases is conducted through line 73 containing valve 74 to pump 75 which discharges through line 76 containing valve 79 into line 34, commingling therein with the insufficiently con-

verted hydrocarbons from fractionator 20 for treatment in the manner described. Light reflux condensate in such cases is conducted through line 80 containing valve 81 to pump 82 which discharges through line 83 containing valve 84 into line 4 wherein such light reflux condensate commingles with the relatively light hydrocarbon oil and is subjected to conversion in commingled state therewith in the manner previously described.

All of the methods of operation described above relate to a process in which the charging stock thereto is a relatively light readily vaporizable hydrocarbon oil, however, as was previously mentioned, relatively heavy difficultly vaporizable hydrocarbon oil or a composite of both readily and difficultly vaporizable hydrocarbon oils may be utilized in a process of this type. In a process operating on either of the two last mentioned types of charging stocks, it is, of course, desirable to separate both light and heavy reflux condensates in fractionator 48, thus eliminating the one operation in which total reflux condensate from fractionator 48 is returned to the catalytic cracking step. The relatively heavy difficultly vaporizable hydrocarbon oil or the composite charge is supplied through line 85 containing valve 86 to pump 87. Pump 87 discharges through line 88 and the oil in line 88 may be directed through valve 89 into fractionator 48 wherein it undergoes fractionation in commingled state with the reaction products supplied to fractionator 48 in the manner previously described, or the hydrocarbon oil in line 88 may be directed through line 90 containing valve 91 into line 76, commingling therein with reflux condensate in line 76 after which it is subjected to treatment in the manner previously described.

From the foregoing it is quite obvious that there are many types of operation in which the improved form of this invention is useful, and it is my intention, therefore, not to limit the invention to any of the specific types of operation herein disclosed but rather to apply it generally to all types of operation in which a pyrolytically formed gasoline is produced which may show improvements in octane rating by catalytic treatment of the type herein described.

An example of one specific operation of the process as it may be accomplished in an apparatus such as illustrated and above described is approximately as follows: The charging oil, a 33° A. P. I. gravity Mid-Continent gas oil, is heated to a temperature of about 950° F. The resulting heated vapors under a pressure of about 30 pounds per square inch are passed in contact with a mass of silica-alumina catalyst of the type previously mentioned at a liquid hourly space velocity of 4.

Conversion products leaving the mass of cracking catalyst are commingled with a gasoline distillate separated in the manner to be described and the resulting mixture passed in contact with a second mass of cracking catalyst at a liquid hourly space velocity of 15. Conversion products leaving the last mentioned mass of cracking catalyst is fractionated to separate fractionated vapors of the gasoline boiling range from the higher boiling insufficiently converted hydrocarbons and the former subjected to cooling and condensation and recovered as a product of the process.

Insufficiently converted hydrocarbons separated in the manner described are commingled

with a heavy reflux condensate the mixture subjected to pyrolytic conversion in a heating coil and communicating reaction chamber at a temperature of about 920° F. and a superatmospheric pressure of 200 pounds per square inch at the outlet of said reaction chamber. Reaction products leaving said reaction chamber are supplied to a vaporizing and separating chamber wherein vaporous reaction products are substantially separated from non-vaporous liquid residue and the latter recovered as a product of the process.

Vaporous reaction products separated in the manner described are fractionated to separate fractionated vapors of about the gasoline boiling range, light reflux condensate having an end boiling point not substantially in excess of 650° F., and heavy reflux condensate. The heavy reflux condensate is supplied to the pyrolytic cracking step and the light reflux condensate to the catalytic cracking step. The fractionated vapors are separately heated to a temperature of 950° F. and the heated vapors thereafter commingled with the conversion products from the first catalytic cracking zone and the resulting mixture supplied to a second catalytic cracking zone in the manner previously described.

From an operation employing conditions as above described one may obtain approximately 72% of 76 octane rating gasoline, approximately 11% of non-vaporous liquid residue, the balance being principally carbon, gas, and loss.

We claim as our invention:

1. In a process for the conversion of hydrocarbon oil wherein relatively light readily vaporizable hydrocarbons are vaporized and heated to a cracking temperature and subjected to catalytic conversion in a zone containing catalyst capable of effecting the desired cracking reaction, and relatively heavy difficulty vaporizable hydrocarbons are subjected to pyrolytic cracking, insufficiently converted hydrocarbons from the catalytic cracking step, including those boiling above gasoline are supplied to the pyrolytic cracking step, the method which comprises commingling gasoline from the pyrolytic cracking step with the conversion products from the catalytic cracking step, and subjecting the resultant mixture to treatment in a catalyst zone separate from the catalytic cracking zone at a liquid hourly space velocity higher than that maintained in said catalytic cracking step to improve the octane rating of such gasoline.

2. The improved process of claim 1 further characterized in that the gasoline supplied to the catalytic treatment contains dissolved and condensed normally gaseous hydrocarbons.

3. A process for the conversion of hydrocarbon oil which comprises maintaining a catalytic cracking zone and a pyrolytic cracking zone, separately fractionating conversion products from both cracking zones to separate fractionated vapors, including hydrocarbons boiling within the range of gasoline from higher boiling insufficiently converted hydrocarbons, supplying higher boiling insufficiently converted hydrocarbons from the catalytic cracking step to said pyrolytic cracking zone, supplying higher boiling insufficiently converted hydrocarbons from the pyrolytic cracking step to the said catalytic cracking zone, heating fractionated vapors formed in the pyrolytic cracking step to a conversion temperature, and commingling such heated vapors with the conversion products from said catalytic con-

version step and subjecting the mixture to treatment in a catalyst zone separate from the catalytic cracking zone at a liquid hourly space velocity higher than that maintained in said catalytic cracking zone to improve the octane rating of the heated vapors.

4. A process for the conversion of hydrocarbon oil which comprises maintaining a catalytic cracking zone and a pyrolytic cracking zone, separately fractionating conversion products from both cracking zones to separate fractionated vapors, including hydrocarbons boiling within the range of gasoline from higher boiling insufficiently converted hydrocarbons, supplying higher boiling insufficiently converted hydrocarbons from the catalytic cracking step to the pyrolytic cracking step, further separating the higher boiling insufficiently converted hydrocarbons from the pyrolytic cracking step into light and heavy reflux condensates, supplying said heavy reflux condensate to the pyrolytic cracking step, supplying the light reflux condensate to the catalytic cracking step, heating the fractionated vapors from the pyrolytic cracking step, and commingling such heated vapors with the conversion products from said catalytic cracking step and subjecting the mixture to treatment in a catalyst zone separate from the catalytic cracking zone at a liquid hourly space velocity higher than that maintained in said catalytic cracking zone to improve the octane rating of the heated vapors.

5. In a process for the conversion of hydrocarbon oil wherein relatively light readily vaporizable hydrocarbons are vaporized and heated to a cracking temperature and subjected to catalytic conversion in a zone containing catalyst capable of effecting the desired cracking reaction, and relatively heavy difficulty vaporizable hydrocarbons are subjected to pyrolytic cracking, insufficiently converted hydrocarbons from the catalytic cracking step, including those boiling above gasoline are supplied to the pyrolytic cracking step, the method which comprises introducing gasoline from the pyrolytic cracking step to the catalytic cracking zone at some selected intermediate point so that such gasoline passes in contact with the catalyst in said catalytic cracking zone at a relatively higher liquid hourly space velocity than the total reactants supplied to such zone.

6. A hydrocarbon conversion process which comprises pyrolytically cracking a relatively heavy oil to form thermally cracked gasoline, simultaneously subjecting a lighter oil to catalytic conversion in contact with a cracking catalyst, commingling at least a portion of said gasoline with the resultant catalytic conversion products, and subjecting the resultant mixture at conversion temperature to contact with cracking catalyst at a liquid hourly space velocity higher than that maintained in the first-mentioned catalytic conversion step.

7. A conversion process which comprises catalytically cracking hydrocarbon oil, commingling thermally cracked gasoline with the resultant catalytic conversion products, and subjecting the resultant mixture at conversion temperature to contact with cracking catalyst at a liquid hourly space velocity higher than that maintained in the first-mentioned catalytic conversion step.

ROLAND B. DAY.
